[57] CLAIM

The ornamental design for a probe cover, as shown and described.

DESCRIPTION

FIG. 1 is a perspective view of a probe cover showing my new design;

FIG. 2 is a front elevational view thereof;

FIG. 3 is a side elevational view thereof;

FIG. 4 is a top plan view thereof;

FIG. 5 is a bottom plan view thereof.

The sides opposite those shown in FIGS. 2 and 3 are essentially mirror images thereof.
